H. G. RICE

HOLDER FOR SOCKET WRENCH SETS

Filed Feb. 18, 1926

Inventor:
Harold G. Rice
By Frank, Tavel, Clapp & Son, Atty's

UNITED STATES PATENT OFFICE.

HAROLD G. RICE, OF CHICAGO, ILLINOIS.

HOLDER FOR SOCKET-WRENCH SETS.

Application filed February 18, 1926. Serial No. 89,065.

This invention relates to holders for socket wrench sets which consists of, for example, a plurality of graduated sizes of sockets, a screw driver socket member and 5 a bent-end handle member. One object of the invention is to provide such a holder in which the sockets are compactly arranged and in which the handle member is firmly held in position and utilized to hold the 10 socket members in place in the holder.

Another object is to provide such a holder which will be light in weight and strong and rigid, and which will be convenient in use and easy to manufacture.

15 Other objects and advantages of the invention will become apparent when reference is had to the following specification, when considered in connection with the accompanying drawing, in which:—

20 Fig. 1 is a plan view of the holder.

Fig. 2 is a side elevation.

Fig. 3 is a longitudinal section, and

25 Figs. 4 and 5 are sections on the lines 4—4 and 5—5 respectively of Fig. 2.

Referring now to the drawings wherein I have illustrated a selected embodiment of 30 my invention, 6 represents the sockets, 7 a handle member having a bent end 8 and straight end 9, and 10 a screw driver member. The handle member is preferably of hexagonal cross section such as is commonly used in devices of this kind and the straight end 9 of the handle is adapted to be used in turning the sockets when the bent end 8 is 35 inserted into the proper end of one of the sockets in a well known manner.

The holder comprises a housing 11 having a bottom wall 12 which is wide enough at one end to receive the largest socket of the 40 set and tapers towards the other end to receive the smallest socket of the set. Side flanges 13 and 14 extend upwardly from the bottom 12 to prevent lateral displacement of the socket members and are preferably 45 integral with the bottom. At the narrow end of the housing 11, I provide a stop or closure member to prevent endwise displacement of the small sockets, preferably by bending upwardly an arm or extension 12' 50 of the bottom 12. A cup or receptacle 15 may conveniently be secured to the closure

member 12' for the purpose of providing means for receiving and holding the straight end of the handle member.

While I prefer to provide a separate cup 55 member 15, I may in lieu thereof, strike out a plurality of lugs from the closure member 12' in such positions that the straight end of the handle member would be received and held in position thereby, or I may merely 60 provide an aperture in the closure member through which the said end of the handle may pass. In the present embodiment of the invention I find it convenient to place the screw-driver socket member 10 at the 65 narrow end of the housing, and in order to enable this member being placed at the extreme end against the closure member, I provide a slot 16 in the lower side of the cup member 15 into which the screw driver edge 70 may be slid.

The handle member 7 is of such length that when the straight end 9 thereof is inserted into the receptacle 15 as shown in 75 Figs. 1, 2 and 3, and positioned over the sockets in the holder, the bent end 8 will extend downwardly adjacent the large socket. In order to maintain the handle in this position, and thereby to hold the sockets in the housing 11, I provide a cap member 17 80 which is shaped to substantially conform to the shape of the bent end of the handle, and which is provided with attaching ears 18 and 19 whereby it is pivotally secured to the ends of the side flanges 13 and 14 respectively, by any suitable means, for example, rivets 20 and 21.

To prevent lateral displacement of the bent end of the handle member, I provide lugs or lips 22 and 23 extending downwardly from the cap member 17 so as to embrace the handle as best shown in Figs. 2 and 4. The cap member 17 is normally held in closed or locked position over the handle member as shown in Fig. 2, because of the 95 fact that the pivotal connection between the cap and the housing 11 is spaced inwardly from the end of the handle member when in position in the holder. Upward movement 100 of the bent end 8 of the handle member, being on the outside of the pivotal connection, tends to swing the cap 17 inwardly and

thereby more firmly lock the cap in its closed position. However, if desired, the lip members 22 and 23 may be bent towards the handle slightly, so as to form a clip over the handle to prevent accidental opening of the cap. Additional lugs or lips 24 and 25 may be provided to engage the bent end 8 of the handle in the same manner as above described in regard to lips 22 and 23.

10 When the holder is to be opened so that the handle and one of the sockets may be withdrawn, the cap 17 is merely turned on its pivots to the position shown in Fig. 3 wherein it serves as a leg for supporting 15 that end of the holder while the other or narrow end of the holder may rest directly on the bench or other support on which it is laid.

I am aware that changes may be made in 20 the form and construction of my improved connector without departing from the essence of the invention and I therefore reserve the right to make all such changes which fall within the scope of the following 25 claims.

I claim as my invention:

1. In a holder for holding a set of sockets in a row and a socket wrench handle member in packed position adjacent the row of 30 sockets, the combination of a tray for receiving a set of sockets, a part at one end of said tray having a recess for receiving one end of a socket wrench handle member for holding said end in packed position, and an independent cap member connected to said tray adjacent the opposite end thereof so as to be movable relatively thereto and adapted to embrace only a comparatively small portion of said handle member so as to hold 35 the latter end in packed position.

40 2. A holder for holding a set of sockets in a row and a handle member disposed lengthwise of the row and comprising a tray for receiving the set of sockets in a row with 45 the handle member extending over the tops of the row of sockets, and a bifurcated part having its bifurcation straddling the tray and pivotally connected thereto, said part being capable of being swung on its pivotal 50 connection and operative in one position of adjustment to lock said handle member in effective position.

55 3. In a holder for holding a socket wrench set comprising a plurality of sockets and a bent end handle member, a tapered channel housing for holding the sockets in a row, a stop for said sockets at one end of said housing comprising an upwardly extending arm, means for holding the handle member over 60 the row of sockets comprising means on said arm for receiving and interlocking with the straight end of the handle, and an independent member at the other end of the housing, pivotally mounted on an axis transverse of the length of the housing and

adapted to embrace a portion of the adjacent end of the bent end handle member for holding said adjacent end in position.

4. In a holder for holding a socket wrench set comprising a plurality of sockets and a bent-end handle member in an arrangement wherein the sockets are in a row and the handle is disposed over the sockets with the bent end thereof projecting downwardly adjacent the socket at one end of the row, a 70 housing comprising a tapering bottom having upwardly extending side flanges between which the sockets are retained, an end stop at one end of the housing comprising an arm extending upwardly from said bottom, an axially horizontal cup secured to said arm at an elevation from said bottom and adapted to receive the straight end of said handle member, a cap member pivotally connected to said side flanges and adapted to embrace the bent end of said handle to hold the handle in the desired position.

5. In a holder for holding a socket wrench set comprising a plurality of sockets and a bent-end handle member, a housing comprising a tapering bottom having upwardly extending side flanges between which the sockets are retained, a closure for one end of said housing comprising an upwardly extending lip integral with the bottom and having a recess at its upper end adapted to slidably receive and interlock with the straight end of the handle member and an independent locking member at the other end of the housing for positioning the bent end of the handle member, comprising a member shaped to enclose said bent end, and having a pair of attaching ears extending therefrom and pivotally connected to said side flanges.

6. In a holder of the class described, a housing for receiving a set of sockets in a row and a handle disposed thereover, means at one end of the housing for holding the straight end of the handle and a cap at the other end of the housing pivotally secured thereto for holding the other end of the handle, said pivotal connection being spaced inwardly from the corresponding end of the handle, whereby upward movement of that end of the handle member forces said cap into tighter engagement with the handle member.

7. In a holder for holding a plurality of sockets in a row with the handle disposed over the sockets to retain them in the holder, a housing for receiving the sockets having a bottom provided with side wall members for holding the sockets against lateral displacement on the bottom, means on one end of the housing for holding the straight end of the handle in position adjacent the sockets and means independent of the first mentioned means and pivotally connected to the other end of the housing at a point spaced 120 125 130

inwardly from the bent end of the handle for holding the bent end of the handle adjacent the sockets, said inwardly disposed pivotal connection being effective to prevent disengagement of said independent means from the handle member as an incident to thrust of said adjacent end in a direction extending laterally from the tops of the sockets.

10 8. A holder for holding a set of sockets in

a row and a handle member disposed lengthwise of the row and comprising a tray for receiving the sockets in a row, and means for retaining the sockets in said tray and including a member having a bifurcated part straddling the tray and pivotally connected thereto on an axis extending transverse of the length of the tray. 15

HAROLD G. RICE.
